Attorney,

UNITED STATES PATENT OFFICE.

GEORGE W. ATKINS, OF CLARION, PENNSYLVANIA.

THILL-COUPING.

SPECIFICATION forming part of Letters Patent No. 435,273, dated August 26, 1890.

Application filed April 8, 1890. Serial No. 347,062. (No model.)

To all whom it may concern:

Be it known that I, GEORGE W. ATKINS, a citizen of the United States of America, residing at Clarion, in the county of Clarion and 5 State of Pennsylvania, have invented certain new and useful Improvements in Thill-Couplings, of which the following is a specification.

My invention consists in the novel construction of parts, as hereinafter specified, and especially as the same is particularly pointed out in the claims.

I have fully and clearly illustrated my invention in the accompanying drawings, wherein—

15 Figure 1 is a side view showing my improved key as applied to one end of the coupling. Fig. 2 is a horizontal vertical section. Fig. 3 is a top view. Figs. 4 and 5 are detail views.

A designates the shaft-iron having an eye 20 1, which fits into the space between the bearing-ears 2 3 of the coupling B, where it is secured in place by the coupling-pin 4. The bearing-ear 2 is formed with a small aperture in its side face, substantially as shown in Fig.

25 2 of the drawings, to admit a small object when it is desired to knock out or remove the bolt. The ear 3 is open to receive the coupling-pin, and is provided on its end with a vertically-arranged tapering and dovetailed

30 groove 5, in which the fastening-key 6 is made to slide. This key is made tapering or wedge-shaped, substantially as shown in the drawings, and being formed with bevels 7 8 on its sides to slide in the groove. This key 6 has

35 secured across its center a holding-spring 9, which snaps into the transversely-arranged groove 10, thereby locking the key and pre-

venting it from being jolted out or becoming displaced. To permit the key and locking-spring to be readily inserted, the upper portion of the end face may be beveled, as seen at 11. To withdraw the key, the ends of the spring are raised out of the groove and the key is pushed up in the direction from which it was inserted.

Having thus described my invention, what I claim, and desire to secure by Letters Patent, is—

1. In a thill-coupling, the combination, with the thill-iron, the bearing-pin, and the coupling-ears, one of which is formed with a vertically-arranged dovetailed groove and a transversely-arranged shallow groove, of the fastening-key formed to fit the vertically-arranged groove in the ear of the coupling, and provided 55 with the transversely-arranged spring, substantially as described.

2. In a thill-coupling, the combination, with the thill-iron, the bearing-pin, and the coupling-ears, one of which is formed with a knock-out aperture and the other with a vertically-arranged dovetailed groove and a transversely-arranged shallow groove, of the fastening-key formed to fit the vertically-arranged groove in the ear of the coupling, and provided 65 with the transversely-arranged spring, substantially as described.

In witness whereof I have hereunto set my hand in the presence of two attesting witnesses.

GEORGE W. ATKINS.

Attest:

SAML. K. CLARKE,
A. C. MCCOMB.
